UNITED STATES PATENT OFFICE.

VINCENT G. APPLE, OF DAYTON, OHIO, ASSIGNOR TO THE APPLE ELECTRIC COMPANY,
OF DAYTON, OHIO, A CORPORATION OF OHIO.

LAMP-SOCKET.

1,110,099.

Specification of Letters Patent.

Patented Sept. 8, 1914.

Application filed April 8, 1914. Serial No. 830,370.

To all whom it may concern:

Be it known that I, VINCENT G. APPLE, a citizen of the United States, residing at Dayton, in the county of Montgomery and 5 State of Ohio, have invented certain new and useful Improvements in Lamp-Sockets, of which the following is a specification.

This invention relates to improvements in sockets for incandescent electric lamps.

My improved socket is particularly adapted for use with the lighting systems of motor cars, where the apparatus is subjected to great hardships as compared with house lighting systems or the like, where there is 15 no vibration and the socket is protected from the elements.

Motor car lighting systems are frequently installed by workmen and used by persons unfamiliar with electrical matters and one 20 of the objects of my invention is to provide a socket that is practically "fool-proof" and can be installed without the liability of an accidental ground.

Another object of my invention is to provide a hardy, efficient socket, easily manufactured without requiring the use of special tools other than those ordinarily found in a shop where electrical apparatus is produced.

Another object of my invention is the provision of a socket in which the two current-carrying wires are led into the base from the rear end thereof and are readily connected to the lamp terminals from the outside of the socket by soldering or the like.

Other and further objects of the invention will be apparent to those skilled in the art from a consideration of the following specification and drawings in which;

Figure 1 is an elevation of my improved socket showing a lamp inserted therein. Fig. 2 is a vertical sectional view through the socket. Fig. 3 is an elevation of a lamp showing one form of base particularly adapted for use with my improved socket. 45 Fig. 4 is an enlarged transverse sectional view on the line 4—4 of Fig. 2. Fig. 5 is an enlarged transverse sectional view on the line 5—5 of Fig. 2. Fig. 6 is a similar transverse sectional view on the line 6—6 of 50 Fig. 2. Fig. 7 is a similar transverse sectional view on the line 7—7 of Fig. 2. Fig. 8 is an enlarged vertical sectional view through the central contact plunger, and Fig. 9 is an enlarged perspective view show-

ing the terminal plate to which the central contact is connected.

The numeral 10 indicates a cylindrical base part made of fiber, bakelite, or other readily moldable insulating material. This base part is of two diameters, the part 11 60 which receives a contact cylinder 12 and insulating sheath 13 being reduced in diameter twice the thickness of the two coverings so that when the socket is completed, and the insulating sheath in place, the entire structure is of a uniform diameter equal to the diameter of the larger portion of the base part 10.

The metallic contact cylinder 12 makes a tight fit over the reduced portion 11 of the 70 insulating base part and projects beyond the end of the base sufficiently far to receive the base part 14 of an incandescent lamp. In the particular embodiment of my invention illustrated I have shown the socket as of the 75 Ediswan type, the projecting pins 15 on the lamp base passing into the slots 16 formed in the cylinder 12 and on partial rotation thereof engaging with the off-set passages 17, of this bayonet-engaging member.

A metal plug 18 is pressed into a central opening in the inner end of the base extension 11 and is bored out as at 19 to receive a spring 20, and plunger 21. The plunger is centrally bored, as at 22, and is provided 85 with an annular shoulder 23 at its inner end so that after being inserted in position the outer end of the plug 18 is turned over inwardly as at 24 and the spring pressed plunger thus held in position. This plunger 21 90 forms a yielding central contact for the button 25 on the center of the lamp base.

A substantially square opening 26 is provided by cutting away from the cylinder 12, a part of its inner end thus exposing a portion of the insulated base part 11. A metal plate 27 curved to conform to the cylinder 12 and of a size somewhat less than the opening 26 overlies the exposed part of the base 11. This plate 27 is provided with a 95 pin 28, radially disposed with respect to the arc of the plate, and of a length sufficient to extend through an opening in the base 10 and into a hole 29 provided therefor in the plug 18. This pin 28 serves the three functions of fastening the plate 27 in position, locking the plug 18 within the central opening in the base 10, and providing an elec- 100 105

trical conductor between the central lamp plug 21 and the plate 27, to which a terminal wire is fastened.

My improved connector for the wire terminals is illustrated in Fig. 9, a perspective view of the plate 27. Two parallel slots are cut in the plate 27 and the ribbon 30 formed by the two slots is bent inward in the form of a loop, a recess or slot 30' being formed in the base 11 to receive the loop. The wire can thus be inserted between the plate 27 and the loop 30 and secured in place by solder 31. A similar loop 32 is formed in the cylinder 12 at the side positioned opposite from the plate 27, a recess 32' being cut in the base to receive it. Obviously the loop 32 must be formed after the cylinder 12 is in position. This is accomplished by pressing the ribbon, formed by the two parallel cuts, into the recess 32'. Holes 33 and 34 are formed in the base member 10 and positioned to register with the openings formed between the loops 30 and 32 and their respective parts. The openings 33-34 are enlarged at their outer end as at 35 and 36 to receive the insulated ends 37 and 38 of the two wires 39 and 40. After the wires 39 and 40 have been inserted in the insulating base and securedly soldered in place, an insulating sheath 13, of fiber or the like, is placed over the cylindrical metal part 12, thus insulating the entire socket. And as the outside diameter of the sheath 13 is the same as the outer diameter of the base 10 a smooth exterior surface is provided.

A pin 41 extends through the sheath 13, the metal cylinder 12 and into the base part 11, at a point intermediate the terminal connections, thereby locking the sheath and metal parts in place. Whereas the pin 41 serves to lock the cylinder against accidental displacement it is evident that an additional lock is formed by the bending inward of the loop 32 into the recess 32' in the base 11.

Having described my invention, what I claim is:—

1. The combination in an incandescent lamp socket, of an insulating base part; a metallic cylinder, surrounding a part of the base and providing one contact for the lamp, said cylinder having a portion of its periphery cut away; a plate, curved to conform to the curvature of the cylinder mounted on said base part in the cut away portion of the cylinder and spaced at all points from said cylinder; a central lamp contact, within said body part; means, connecting said central contact with the plate; and means,

for the attachment of conductors to the plate and to the cylinder.

2. The combination in an incandescent lamp socket, of an insulating base part; a metallic cylinder, surrounding a part of the base and providing one contact for the lamp, said cylinder having a portion of its periphery cut away to expose the base part; a plate, curved to conform to the curvature of the cylinder, mounted on said base part in the cut away portion of the cylinder, and spaced at all points from said cylinder; a central lamp contact, within said body part; means, connecting said central contact with the plate; and strips, cut from said plate and cylinder and bent inwardly to provide conductor-connecting parts.

3. The combination in an incandescent lamp socket, of an insulating base part; a metallic cylinder, surrounding a part of the base and providing one contact for the lamp, said cylinder having a portion of its periphery cut away to expose the base part; a plate, curved to conform to the curvature of the cylinder, mounted on said base part in the cut away portion of the cylinder, and spaced at all points from said cylinder; a central lamp contact, within said body part; means, connecting said central contact with the plate; and strips, cut from said plate and cylinder and bent inwardly to provide conductor-connecting parts, said base part being cut away to receive said inwardly bent strips, said base part, having openings extending therethrough and registering with the said conductor connecting parts.

4. The combination in an incandescent lamp socket, of an insulating base part; a metallic cylinder, surrounding a part of the base and providing one contact for the lamp, said cylinder having a portion of its periphery cut away; a plate, curved to conform to the curvature of the cylinder mounted on said base part in the cut away portion of the cylinder and spaced at all points from said cylinder; a central lamp contact, within said body part; means, connecting said central contact with the plate; means, for the attachment of conductors to the plate and to the cylinder; and an insulating sheath, surrounding said cylinder and plate.

In testimony whereof I hereunto set my hand in the presence of two subscribing witnesses.

VINCENT G. APPLE.
